United States Patent Office

Des. 183,849
Patented Nov. 4, 1958

183,849

TRIPLE DRESSER

John J. Lubberts and Lambert J. Mulder, Grand Rapids,
Mich., assignors to Thomasville Chair Company,
Thomasville, N. C., a corporation of North Carolina

Application July 11, 1957, Serial No. 46,905

Term of patent 7 years

(Cl. D33—6)

FIG. 1.

FIG. 3.

The back of the triple dresser is conventional and the side not shown is identical to the side that is shown.

We claim:

The ornamental design for a triple dresser, substantially as shown, and described.
